F. C. PRENTICE

FLOOR JACK

Filed Oct. 24, 1925

Patented Mar. 23, 1926.

1,577,491

UNITED STATES PATENT OFFICE.

FRED C. PRENTICE, OF GREAT BEND, PENNSYLVANIA.

FLOOR JACK.

Application filed October 24, 1925. Serial No. 64,634.

To all whom it may concern:

Be it known that I, FRED C. PRENTICE, a citizen of the United States, residing at Great Bend, in the county of Susquehanna and State of Pennsylvania, have invented certain new and useful Improvements in a Floor Jack, of which the following is a specification.

This invention relates to floor jacks, and has for one of its objects to provide a jack for use with flooring boards more particularly of the tongue and groove type for forcing said boards into close abutting relation when laying the floor and for maintaining the same in such a position during the nailing operation without requiring the presence of the workman at the jack.

A further object of the invention is to provide means for preventing vertical raising of the jack during its clamping operation, which is a disadvantage with a majority of jacks now upon the market.

A further and important object is to provide a highly efficient jack of relatively few parts to be manipulated to a clamping or unclamping position without requiring any great skill upon the part of the workman.

With the foregoing and further objects in view as the nature of the invention is better understood, the same comprises the novel form, combination and arrangement of parts, hereinafter more fully described in the accompanying drawing and claimed.

In the drawing wherein like reference characters indicate corresponding parts throughout both the views:

Figure 1 is a top plan view of my improved floor jack in actual use, and

Fig. 2 is a longitudinal section, partly in side elevation of said jack.

Now having particular reference to the drawing, my novel jack constitutes the provision of a substantially rectangular shaped and flat-like head 5 that is formed throughout its length with a passageway 6 for the sliding reception of the relatively elongated ratchet bar 7 which ratchet bar is equipped at its forward end with the usual board engaging head 8 that has pivotal connection with the ratchet bar as at 9 for obvious purposes.

Formed integrally with the head 5, and extending longitudinally therefrom, is a slightly upwardly curved bar 10 that is formed at its rear end with a foot 11 for

resting upon the sub-flooring or flooring supporting joists for preventing any upward movement of the jack during the operating of the same, and for also cooperating with other means hereinafter more fully described in limiting the rearward sliding movement of the jack while under operation.

The top side of the head 5 is formed centrally with an opening 12 in communication with the longitudinal passageway 6 of the head, and formed with the sides of this opening extending vertically therefrom are ears 13-13 between which is pivotally secured as at 14, the lower sleeved end of a tubular handle bar 15, the upper end of which is threaded for the reception of a cap 16, Fig. 2.

Slidably disposed within said handle bar is a relatively elongated pin 17 that has a pointed projecting end 18 projecting outwardly from the lower end of the bar for engagement with the teeth on the top surface of the ratchet bar 7. This pin 17 is slidably disposed within the handle bar 15 and is formed adjacent its forward pointed end with a slot 18 thru which projects the pin of the pivotal connection between the bar and the ears 13-13, said pin obviously limiting the movement of the pin 17 in reverse direction by reason of its engagement with the end of the slot in opposite movement of the pin. Said pin 17 is normally maintained in engagement with the teeth of the ratchet bar through the medium of an expansible helical spring 19 disposed within the handle bar between the cap 16 and end of the pin 17, for obviously allowing the pointed end of the pin 17 to ratchet over the teeth of the bar 7 in the upward swinging movement of the handle bar.

The teeth of the ratchet bar are so arranged as to catch the pointed end of the sliding pin in order that the same will be moved forwardly of the head 5 when the tubular handle bar 15 is swung rearwardly so that the board A will be brought or moved into interlocking engagement with the adjacent board which has already been laid.

In order to maintain the ratchet bar 9 in its forced position, a conventional dog 21 is provided at the forward end of the head 5, the same being pivotally disposed as at 22 between spaced ears 23-23 formed at the forward end of said head, it being obvious that when this pawl is raised, the ratchet bar

2
and its board engaging clamp 8 may be moved rearwardly out of engagement with the board that has been acted upon.

The head 5 is equipped upon its lower side with a suitable number of rearwardly inclined spurs 24 that bite into the sub-flooring or main flooring joists primarily for the purpose of preventing a rearward sliding movement of the jack while under operation.

10 The operation and advantages of a jack of this character will be readily appreciated by those skilled in the art even though I have herein shown and described the most preferred embodiment of the invention with 15 which I am at this time acquainted, it is nevertheless to be understood that minor changes may be made in the construction without departing from the spirit and scope of the appended claims.

20 Having thus described my invention, what I claim as new and desire to secure by Letters-Patent is:—

1. In a floor jack, a head, a rack bar slideable longitudinally through said head, a 25 floor board engaging member carried by the forward end of said rack bar, a hollow lever pivoted adjacent its lower end on said head, a ratchet pin slidably disposed within the lever, the lower end cooperating with the 30 ratchet teeth of said rack bar whereby the bar may be moved in one direction through the medium of the hollow lever and the pin, and means for maintaining the rack bar in its adjusted position.

2. In a floor jack, a head having a longitudinal passage formed therein, a rack bar slideable through the passage in said head, a floor board engaging member upon the forward end of the bar, a hollow lever pivoted 40 adjacent its lower end on the top side of said head, a ratchet pin slidably disposed within the lever and adapted for cooperation with the teeth of the rack bar, said head being provided with an opening in the top

side thereof in communication with the rack 45 bar passage for permitting the cooperation between the lower end of the pin and the rack bar whereby the rack bar may be forced in one direction through the medium of the hollow lever and pin, and a pivoted pawl 50 mounted on said head and cooperating with the ratchet teeth of the rack bar for holding the same in its adjusted position.

3. In a floor jack, a head, having a longitudinal passage formed therein, the top side 55 of said head having an opening arranged therein in communication with said passage, a rack bar slideable through said passage, a floor board engaging head member carried by the forward end of the rack bar, and a pair of upstanding ears on the top side of the head on opposite sides of the opening, a pivot pin journaled at its respective ends in the upper portions of said upstanding ears, an elongated tubular handle bar having its lower end open and supported adjacent its lower end on said pin between said ears, a closure for the upper end of the tubular handle bar, a ratchet pin slidably disposed within the tubular handle bar, the lower portion of said pin being provided with a longitudinal slot through which the pivot pin extends, the lower end of the ratchet pin 60 extending outwardly of the lower open end of the hollow handle and downwardly into the passage formed in said head, a coil spring disposed within the upper closed end of the handle bar for normally urging the pin into cooperative relation with the ratchet teeth of the rack bar, whereby the bar may be moved forwardly of said head when the handle bar is swung rearwardly, and a pivoted locking pawl mounted on said head and cooperating with the ratchet teeth 65 of the rack bar for holding the latter in its adjusted position.

In testimony whereof I affix my signature.
FRED C. PRENTICE.
